WALTER R. CLARK, OF BRIDGEPORT, CONNECTICUT, ASSIGNOR TO BRIDGEPORT
BRASS COMPANY, OF BRIDGEPORT, CONNECTICUT, A CORPORATION OF CON-
NECTICUT.

ТИЛТИНГ ФУРНАСЕ ОР ЛІКЕ СТРУКТУРЭ.

1,358,621.

Specification of Letters Patent. Patented Nov. 9, 1920.

Application filed April 19, 1919. Serial No. 291,237.

To all whom it may concern:

Be it known that I, WALTER R. CLARK, a citizen of the United States, residing in Bridgeport, in the county of Fairfield and

5 State of Connecticut, have invented certain new and useful Improvements in Tilting Furnaces or like Structures, of which the following is a full, clear, and exact description.

10 This invention relates to furnaces and like structures, adapted to be tilted for the pouring off of molten metal, and it has particular reference to mechanism for pivotally mounting the furnace or the like upon sup-

15 porting brackets and to mechanism for counterweighting the furnace in order that the same may be easily tilted.

One object of my invention is to provide improved means for pivotally mounting a furnace receptacle between spaced supporting frames whereby the molten metal may be easily and efficiently poured from its receptacle into the molds.

Another object of my invention is to provide improved means for counterbalancing the weight of the furnace receptacle in order that the receptacle may be more readily tilted to pour the molten metal from the same.

30 Still another object of my invention is to provide a tilting furnace construction in which the frame for supporting the furnace receptacle, and the means for tilting and counterbalancing the receptacle are so con-

35 structed that the entire furnace construction requires a minimum amount of floor space.

It has been recognized heretofore that the tilting of the furnace about an axis substantially in horizontal alinement with the pour-

40 ing spout of the furnace body is of advantage, because the molten metal has a uniformly small distance to travel from the spout to the mold throughout the pouring operation. By this arrangement, the pouring into the molds is made much more accurate and expeditious, and there is much less waste than in the case where the metal, during at least a part of the operation, has to travel a long arc, before reaching the

50 mold—a drawback incident to the pivoting of the furnace receptacle at or about the center thereof in the ordinary way. My invention, therefore, relates to a furnace construction in which this defect is avoided,

but wherein, nevertheless, the construction 55 of the apparatus is more simple, and its operation more easy and convenient than in prior devices.

To these and other ends, the invention consists in the novel features and combinations of parts to be hereinafter described and claimed.

In the accompanying drawings:

Figure 1 is a front elevation of a tilting furnace structure embodying my invention. 65

Fig. 2 is a side elevation of the same, part of the gear casing being removed in order to disclose the interior of the same.

Fig. 3 is a view similar to Fig. 2, but showing the furnace receptacle in its tilted 70 position.

Fig. 4 is a plan view of the device, shown in Fig. 1.

Fig. 5 is a fragmentary side view of my device, taken substantially on line 5—5 of 75 Fig. 1.

Fig. 6 is a modification showing a side view of my tilting furnace with the side supporting frame removed, in order to disclose a different construction of the counter-weighting mechanism; and 80

Fig. 7 is a view similar to Fig. 6, showing another modification of my invention.

In the drawings, I have shown my invention applied to an electric induction furnace for melting brass scrap and other metals, although it will be obvious that the character of the furnace may be radically varied without departing from the principles of the invention, and that if desired, 85 the invention may be applied to various types of furnace receptacles. The furnace receptacle is designated in its entirety by the numeral 10, and this receptacle is positioned between a pair of spaced hollow side 90 frames 11 and 12, upon which it is pivotally mounted, in the manner hereinafter described. The receptacle 10 is preferably provided with a side door 13, and a top door or lid 14, the latter being swung to its open 95 position by means of the operating lever 15. Upon the side of the furnace receptacle, opposite the door 13, is provided the pouring spout 16, which is positioned some distance below the upper end of the receptacle. The 100 furnace receptacle is preferably made in sections, which sections are secured together by a plurality of bolts, as shown.

The particular construction of the furnace receptacle, however, is not important, so far as the invention herein described is concerned.

5 My preferred means for pivotally mounting the furnace receptacle upon its supporting frames 11 and 12, consists in providing the brackets 17 and 18, which may be formed integral with or bolted to the furnace receptacle, as desired, these brackets being provided with trunnions 19 and 20, formed upon their outer ends, the brackets being constructed and arranged so that the trunnions positioned upon the opposite sides of 10 the pouring spout 16 lie substantially in alignment with this spout, so that the mouth of the spout lies substantially at the axis about which the furnace receptacle swings when the same is tilted to its pouring position. The trunnions 19 and 20 are rotatably mounted in bearing members 21 and 22 rigidly mounted upon the frames 11 and 12, and preferably upon one edge of these frames, as shown in the drawings. The frames 11 and 12 are made hollow, for the reason hereinafter pointed out, and they are preferably built up of angle irons and sheet metal plates as shown, each frame being constructed of the sheet metal side plates 23 and 24, which are retained in spaced relation to each other by any desired type of angle plates to which they are riveted.

15 The mechanism which I have provided for tilting the furnace receptacle about its trunnions will now be described. On each side of the furnace receptacle 10 are mounted curved guides 25 and 26, which are rigidly secured to the receptacle by bolts or the like 27. These curved guides are grooved, as 20 shown, to receive the chains 28 and 29, the lower end of which chains are rigidly secured to the lower end of the curved guides by any preferred means, such as bolts 30. Upon the upper end of the frames 11 and 25 12 are rigidly mounted bearing brackets 31, 32, 33 and 34, in which the horizontal shafts 35 and 36 are rotatably mounted, and upon each of these shafts are mounted the chain receiving wheels or sheaves 37, 38, 39 and 40, these sheaves being rigidly secured to their shafts. The upper end of the chains 28 and 29 are wound around the sheaves 38 and 39, and the last link of these chains is rigidly secured to its sheave by any preferred means (not shown), the arrangement being such that when the shafts 35 and 36 are rotated, the chains 28 and 29 will be either wound upon or unwound from the chain receiving wheels 38 and 39. Since the 30 trunnions about which the receptacle 10 swings are positioned considerably to one side of the center of gravity of the receptacle, it is very desirable to provide counterweighting means to assist in tilting the furnace receptacle. For this purpose, I have

provided the counterbalancing weights 41 and 42, which are slidably mounted within the hollow frames 11 and 12, these weights preferably being made up of a number of separate weights, which are secured together 70 by bolts 43. In this manner, the total weight of the counterbalancing members 41 and 42 may be increased or decreased, as desired. These weights are operatively connected to the sheaves 37 and 40 by chains or 75 the like 44, the shafts 35 and 36 being so positioned upon the frames 11 and 12 that the weight supporting chains 44 hang vertically from the periphery of the wheel about which they are wound, so that the weights 80 will slide freely up and down within the hollow frames. The operating means which I have provided for tilting the furnace receptacle consists of the relatively large hand wheel 45, which is operatively connected to the vertical shaft 46 by means of the bevel gears 47 and 48, the shaft 46 in turn being operatively connected to the horizontal shaft 36 by means of a worm 49 and worm gear 50, the worm gear being rigidly secured to 90 the shaft 36 and the gears 49 and 50 being preferably housed in a gear casing 51.

95 The operation of my device will now be described. When it is desired to tilt the furnace receptacle 10 from its vertical position to the tilted position shown in Fig. 3, the hand wheel 45 is rotated in order to rotate the shaft 36 by means of the mechanism, just described, so that the chain receiving wheel 39 will be rotated in a direction to 100 wind the chain 29 about the same. As this is done the chain 29 will exert a pull upon its curved guide 26 sufficient to tilt the receptacle 10 to the pouring position, as shown in Fig. 3, the operation of the tilting mechanism being materially assisted by the counterweights, above described.

105 It is unnecessary to provide the hand wheel 45 with means for operatively connecting it to the horizontal shaft 35, since 110 it is obvious that if sufficient power is imparted to the shaft 36, the furnace receptacle will be swung either toward or from its tilted position, as may be desired. The counterweights 41 and 42 will impart a sufficient 115 rotating force to the shafts 35 and 36 to make the mechanism operate smoothly, but these weights are not sufficiently heavy to entirely counteract the weight of the receptacle, since in the mechanism, which I 120 have disclosed, the hand wheel 45 and mechanism operated thereby is provided to lift the furnace receptacle to its tilted position, and the weight of this receptacle is dependent upon to return the parts to their normal 125 position.

130 In the modification of my invention shown in Fig. 6, the construction and operation of my device is the same as in Figs. 1 and 5 inclusive, except that the curved guide 26' is

positioned upon the receptacle 10' so that the groove in the guide lies eccentric to the axis about which the furnace receptacle tilts. The curved guide 26' is positioned upon the receptacle so that the upper and lower ends of the grooved path formed for the cable are closer to the axis of rotation than the intermediate portion of the groove formed in this guide, as will be apparent by comparing the curvature of the groove with the curvature of the arc $a-a$ described about the axis of the trunnion 29' as a center. I have used a small circle designated by the reference character C to indicate the approximate center of gravity of the receptacle 10' when the same is full of metal, and as the receptacle is tilted about its trunnions, this center of gravity C will move along the arc $c-c$ so that as the receptacle approaches the position in which the center of gravity C will lie in the horizontal plane of the trunnions 20', the point C will necessarily move away from the vertical plane of the axis of the trunnion. It will, therefore, be seen that the counterbalancing mechanism should exert its maximum tilting force upon the receptacle when the center of gravity C lies in the horizontal plane of the trunnion 20'. In order to accomplish this the point where the cable becomes tangent to the path when the center of gravity of the mass is in horizontal alinement with the axis of rotation, lies the greatest distance from the axis of rotation, the arrangement being such that the cable or the like 29' which connects the weight 41' to the curved guide will exert a smaller tilting force upon the receptacle when it is in the vertical position shown in Fig. 6 than will be exerted when the parts are in the tilted position shown in Fig. 3.

This variable tilting force is desirable because when the axis about which the receptacle tilts is positioned, to one side of and above the center of gravity C of the receptacle, as in the present case the center of gravity moves away from the vertical plane of the axis of rotation as the receptacle is tilted toward the pouring position, so that the weight required to be lifted in tilting the receptacle increases as the point C is moved upward toward the horizontal plane of the trunnions and decreases as this point moves away from this horizontal plane, as will be apparent.

During the tilting of the receptacle 10' the eccentric guide will force the active part of the cable away from the trunnions of the receptacle and thereby increase the length of lever arm acted upon by the cable to tilt the receptacle. The counterbalancing effect of the weight 41' is in this manner increased as the angle to which the receptacle is tilted is increased, up to the point when the center of gravity C is in horizontal alinement with

the axis of revolution. After the center of gravity has passed this point in its upward movement the opposite effect takes place. It will be understood that an eccentric curved guide similar to the guide 26' is preferably provided upon the opposite side of the receptacle. 70

In the modification of my invention shown in Fig. 7, the construction and operation of my device is the same as in Figs. 1-5 inclusive, except that the sheave 39 upon shaft 36, as shown in Figs. 1-5 inclusive, has been replaced by the eccentric sheave 39' and the curved guide 26 has been replaced by the curved eccentric guide 26''. 75

As the receptacle 10' is tilted, the center of gravity moves away from the vertical plane of the axis of rotation, thereby increasing the force required to tilt the receptacle until the center of gravity C' of the mass reaches a point in horizontal alinement with the axis of rotation. After the center of gravity has passed this point in its upward movement, it approaches the vertical plane of the axis of rotation and requires 80 less force to tilt the receptacle as pointed out in the above description of Fig. 6. In order to provide a counterbalancing force which will vary as required, I have provided in Fig. 7 an eccentric sheave or cam 39' rigidly secured to the shaft 36, and upon the furnace receptacle the curved guide 26'' is positioned eccentrically with respect to the axis about which the receptacle swings, the upper end of this guide preferably lying farther 85 from the trunnion of the receptacle than the lower end. This construction causes the length of the lever arms, as represented by the curved groove of the cam 39' and guide 26'' to be varied as the force required to tilt 90 the receptacle is varied. The arm of the cam 39' decreases in length as the center of gravity C' of the receptacle moves away from the vertical plane of the axis of rotation, and increases in length as the center 95 of gravity approaches this plane. The counterbalancing effect of the weight 41' is in this manner kept in equipoise with the force required to tilt the receptacle. The side of the furnace opposite to that shown 100 in Fig. 7, it will be understood is preferably provided with counterweighting means similar to that just described. The cable receiving groove formed in the cam 39' is constructed so that an intermediate portion 105 indicated by 52 lies closer to the axis of rotation of this cam than the rest of this curved groove, and the cam 39' is positioned upon the shaft 36 so that the portion of the groove indicated by 52 will be brought into 110 operative engagement with the cable 29'' as the receptacle is tilted to bring its center of gravity C into the horizontal plane of the axis of the trunnions. This construction causes the length of the lever arms as repre- 115

120

125

130

sented by the curved groove of the cam 39' and guide 26" to be varied in such a manner that the counterweight mechanism will exert at all times the desired tilting force.

5 From the above description, it will be seen that the tilting furnace disclosed in Figs. 1 to 5, inclusive, and also the modifications of the same, disclosed in Figs. 6 and 7, are so constructed that a very compact device is 10 provided whereby the same requires a very small amount of floor space compared with the floor space required by the tilting furnace heretofore used. Furthermore, it will be seen that this compactness of the operating parts is due very largely to the arrangement whereby the counterweights operate within the relatively narrow hollow frames positioned upon the opposite sides of the receptacle.

20 What I claim is:

1. In a tilting furnace or like structure, a receptacle having a pouring spout formed upon one side thereof, trunnions secured to said receptacle upon the opposite sides of said spout, hollow side frames upon which said trunnions are journaled, means for tilting said receptacle, and counterbalancing means assisting to tilt said receptacle including weights slidably mounted in said hollow frames, said weights positioned upon the opposite sides of said receptacle substantially in alignment with the axis of the receptacle.

2. In a tilting furnace or like structure, a receptacle, spaced hollow side frames upon which said receptacle is pivotally mounted, means for tilting said receptacle, comprising a horizontal shaft rotatably mounted in a fixed bearing upon one of said frames and operatively connected to said receptacle, means for rotating said shaft, and counterbalancing means assisting to tilt said receptacle, including a weight slidably mounted in one of said frames and operatively connected to said shaft.

3. In a tilting furnace or like structure, a receptacle, spaced side frames at least one of which is hollow, means for pivotally mounting said receptacle upon said frames, means for tilting said receptacle, comprising a rotatable shaft mounted upon said hollow frame and provided with a flexible member for operatively connecting the same to said receptacle, means for rotating said shaft, and a counterweight tending to rotate said shaft, said weight slidably mounted in said hollow frame and operably connected to said shaft.

4. In a tilting furnace or like structure, a receptacle having a spout formed upon one side thereof, spaced side frames, one of which is hollow, trunnions secured to said receptacle in substantial alignment with said spout and journaled upon said frames, means for tilting said receptacle, and counterweighting means tending to tilt said re-

ceptacle, including a weight slidably mounted in said hollow frame and operatively connected to said receptacle, said frames constructed to lie substantially between parallel planes drawn tangent to the front and rear walls of said receptacle.

5. In a tilting furnace or like structure, a receptacle pivoted to swing about an axis positioned to one side of and above the center of gravity of the receptacle, counterweighting mechanism for said receptacle constructed to exert a gradual increasing tilting force upon said furnace as the center of gravity thereof is elevated to the horizontal plane of the axis of rotation, and to exert a gradual decreasing tilting force upon said receptacle, as it is further tilted, comprising a curved guide having a cable receiving surface, a counterweight, a cable engaging said surface and operatively connecting the counterweight to said guide, said cable receiving surface having its intermediate part constructed to lie a greater distance from the pivoted axis of said receptacle than the rest of said surface.

6. In a tilting furnace or like structure, a receptacle pivoted to swing about an axis positioned to one side of and above the center of gravity of the receptacle, counterweighting mechanism for said receptacle constructed to exert a maximum tilting force upon said receptacle when its center of gravity is elevated to the horizontal plane of the axis of rotation, and to gradually decrease as said receptacle is swung in either direction from this position, comprising a weighted cable, and a curved guide having a cable receiving surface, said surface having its intermediate portion positioned to hold the active portion of said cable a greater distance from said pivoted axis than the remaining portion of said surface.

7. In a tilting furnace or like structure, a receptacle pivoted to swing about an axis located above and to one side of the center of gravity of the receptacle, whereby said center of gravity moves first away from the vertical plane of said axis and then toward said plane as the receptacle is tilted, and counterbalancing mechanism for said receptacle constructed to exert an increasing tilting force upon said receptacle as the center of gravity of said receptacle moves from said vertical plane, and a decreasing force as it moves toward said plane.

8. In a tilting furnace or like structure, a receptacle pivoted to swing about an axis positioned to one side of the center of gravity of said receptacle, whereby said center of gravity moves either toward or from a vertical plane passed through said axis as the receptacle is tilted, counterbalancing mechanism for said receptacle, including a weighted flexible member operably con-

5 nected to said receptacle, and means for increasing the force, tending to tilt said furnace as the center of gravity of said receptacle moves from said vertical plane, and to decrease this force as the center of gravity moves toward said plane.

9. In a tilting furnace or like structure, a receptacle pivoted to swing about an axis positioned to one side of the center of gravity of the receptacle, counterbalancing means for said receptacle, including a weight operatively connected to said receptacle, and a cam and coöperating flexible member constructed to increase the counterbalancing effect of said weight as said furnace is swung in either direction toward the position in which the center of gravity of said receptacle lies in the horizontal plane of its axis of rotation.

20 10. In a tilting furnace or like structure, a receptacle pivoted to swing about an axis positioned to one side of the center of gravity of the receptacle, counterbalancing means for said receptacle, including a weight operatively connected to said receptacle, and a cam and coöperating flexible member constructed to vary the counterbalancing force exerted by said weight upon said receptacle as the latter is tilted.

30 11. In a tilting furnace or like structure, a pivotally mounted receptacle, counterbalancing means tending to tilt said receptacle including a weighted flexible member operably connected to said receptacle, and means coöperating with said flexible member to vary the tilting force exerted by said counterbalancing means with the angle to which the receptacle is tilted.

12. In a tilting furnace or like structure, 40 a supporting frame, a receptacle pivotally mounted thereupon, a curved guide secured to a face of said receptacle, a shaft rotatably mounted upon said frame above said guide, a flexible member operatively connecting said guide to said shaft, and a counterweight for said receptacle suspended from said shaft to hang adjacent said receptacle.

13. In a tilting furnace or like structure, 50 a supporting frame, a receptacle pivotally mounted thereupon, a curved guide secured to a face of said receptacle, a shaft rotatably mounted upon said frame above said guide, a flexible member operatively connecting said guide to said shaft, a counterweight for said receptacle suspended from said shaft to hang adjacent said receptacle, and means

other than said counterweight to rotate said shaft to tilt said receptacle.

14. In a tilting furnace, or the like, a receptacle provided with trunnions positioned to one side of the center of gravity of the receptacle, a pair of spaced hollow side frames having said receptacle pivotally mounted therebetween by means of said trunnions, said frames constructed to lie substantially between planes drawn tangent to the front and rear faces respectively of said receptacle, and counterbalancing means for said receptacle including weights slidably mounted in said frames. 70

15. In a tilting furnace, or the like, a receptacle provided with trunnions positioned to one side of the center of gravity of the receptacle, a pair of spaced hollow side frames having said receptacle pivotally mounted therebetween by means of said trunnions, said frames constructed to lie substantially between planes drawn tangent to the front and rear faces respectively of said receptacle, and counterbalancing means including weights operatively connected to said receptacle and suspended within said frames substantially in alinement with the vertical axis of said receptacle. 75

16. In a tilting furnace or like structure, 80 a body having a spout and pivoted to swing about a horizontal axis substantially coincident with the spout, means for tilting said body, means for counterweighting the same, comprising a curved guide carried by said body, and a weighted flexible member operatively engaging the outer face of said guide, said guide operating to force said flexible member away from the pivotal mounting for said body as the latter is moved from its 95 tilted position, to thereby vary the tilting effect of the counterweight.

17. In a tilting furnace or like structure, 100 a body pivoted to swing about a horizontal axis positioned to one side of the center of gravity of said body, counterweighting means for said body, comprising a curved guide carried by said body, and a flexible member having a weight at one end thereof and its opposite end secured to said guide, said guide operating to force said flexible member away from said axis as said body is swung away from its pouring position. 105

In witness whereof, I have hereunto set my hand on the 10th day of April, 1919.

WALTER R. CLARK.
